2 SHEETS—SHEET 2.

Charles O. Wright, Jr.
Attorney

UNITED STATES PATENT OFFICE.

JOHN O. CROY, OF WASHINGTON, DISTRICT OF COLUMBIA.

AUTOMATIC PISTOL.

1,360,188.

Specification of Letters Patent. Patented Nov. 23, 1920.

Application filed April 24, 1920. Serial No. 376,361.

To all whom it may concern:

Be it known that I, JOHN O. CROY, a citizen of the United States, residing at city of Washington, in the District of Columbia, 5 have invented certain new and useful Improvements in Automatic Pistols, of which the following is a specification.

My invention relates to improvements in automatic pistols.

10 In the ordinary automatic pistol, the recoil of the charge operates a mechanism for firing the cartridge and ejecting the same but in such pistols a considerable amount of power is lost by the necessary rearward movement of the cartridge or some part carrying the same, to operate the firing and ejecting mechanisms and my invention resides in making a pistol in which the firing and the ejecting mechanism is manually operated and thereby utilizing the full power of the charge.

The object of my invention is to provide a pistol of this character in which the firing and ejecting mechanism is operated by the 25 gripping of the stock, causing a member in the stock to move forward and this single forward movement operating both mechanisms.

Another object of my invention is to provide a pistol in which a safety mechanism is provided whereby the accidental gripping of the stock will not fire the cartridge, yet allowing of the automatic operation of the pistol to eject all of the cartridges in the 35 magazine, so that the pistol can be unloaded in the same manner as it is fired.

A still further object of my invention is to provide a pistol in which there is no preliminary operation necessary to start the operation of the pistol, as is necessary in the ordinary pistol using the recoil to fire and reset the same, but the simple gripping of the stock at any time starts the operation of the pistol whether the cartridges are fired 45 or not.

A still further object of my invention is to provide a simple cheap and effective pistol of this character made of few parts and in which access may be readily had to all of 50 the moving parts and having certain details of structure and combination of parts hereinafter more fully described.

In the accompanying drawings.

Figure 1 is a side elevation of my improved pistol with the side plate removed, showing the operating mechanism.

Fig. 2 is a vertical transverse sectional view taken on the line 2—2 Fig. 1.

Fig. 3 is a perspective view of the longitudinally movable barrel showing the operating mechanism therefor, and also the cartridge ejecting mechanism, in their separated relation.

Fig. 4 is a longitudinal horizontal sectional view taken through the magazine, on 65 the line 4—4 Fig. 1.

Fig. 5 is a horizontal sectional view taken on the line 5—5 Fig. 1 and looking in the direction of the arrow.

Fig. 6 is a perspective view of the upper 70 portion of the pistol showing the safety attachment for the firing pin.

Fig. 7 is a perspective of the safety attachment for moving the firing pin in or out so that it will or will not engage the cap of 75 the cartridge.

Fig. 8 is a sectional view of the firing pin showing the safety attachment in operative engagement therewith.

Fig. 9 is a sectional view showing the 80 spring holding means for lock operating mechanism.

Referring now to the drawings 1 represents a frame made of the usual metal and having the stock 2 formed integral therewith and also having the forward extension 3 formed integral all of which forms a cheap and effective manner of making the same and yet having a neat appearance. The frame 1 is of a hollow form to receive the 90 entire operating mechanism, including the barrel and magazine and this entire mechanism is retained in the frame by the plate 4, in its operative part, as will be later described. The stock 2 has its rear edge open 95 as indicated at 5 and in which is pivotally mounted at 6, the member 7, which extends out beyond the stock and adapted to be rocked on its pivot by the gripping of the stock, as will be later described in the complete operation of the pistol. The stock 2 has pivoted therein at 8 the member 9, which is adapted to be engaged by the curved face 10 of the member 7 and rocked upon its pivot 8 for ejecting, loading and firing. 100

The forward extension 3 of the frame 1 has the barrel 11 slidably mounted therein and which as shown is of a rectangular form in cross section and has its outer end beyond the frame 1 of a cylindrical form to give a 110 neat appearance to the pistol. The upper edge of the barrel is held against upward

movement by a flange 12 carried by the upper edge of the frame and formed integral therewith and its lower edge engages the rib 13 formed integral with the side plate 14 of the frame 1, and which also serves as a guide to prevent the lateral movement of the barrel in that direction. The plate 4 closing the frame engages the opposite side of the barrel and therefore the same is contained in a passage corresponding to the shape of the barrel, so that it has a free longitudinal movement in the frame, yet held against lateral movement.

The side of the barrel, adjacent its rear end, is cut away as indicated at 15 and pivoted within this cut away portion at 16 is a link 17, which extends rearwardly and is pivotally connected to the lever 18 at 19. The said lever 18 is pivotally connected to the frame 1 intermediate its ends by the pivot 20 and whereby the rocking of the lever moves the barrel forward and rearward for firing the cartridge and ejecting it, as will be later described. The pivoted member 7 is normally held in its outward position by means of the spring 21 which as shown is a leaf spring but as will be readily understood a coil spring could be used. Pivotally connected to the upper end of the member 9 at 16' is a forked shaped member 22 which extends forwardly and has the lower forked member 23 thereof resting on the upwardly curved raised portion 24 carried by the frame 1 and which lifts the member 22 in its forward movement, for a purpose later described. The member 22 is arranged between two guides 25 which allows of its free forward movement but prevents any lateral movement. The forked member 22 has its upper member 26 passing between the guides 27 carried by the frame 1 and whereby it is free to move longitudinally but held against lateral movement. The forward end of the member 26 is reduced and engages a movable dog 28 carried by the intermediately pivoted lever 18. This dog as shown has a rocking movement on the lever through the pin and slot arrangement 29 and 30 and normally held in the position shown in Fig. 3 of the drawings by the spring 31 shown in dotted line Fig. 1. This arrangement of the dog allows the lever carrying the same to be moved forward by the engagement therewith of the member 26 and allows the member 26 to freely pass over the dog and after the dog has dropped into the slot 32 in the member 26 one is free to move independent of the other and therefore there will be no frictional engagement between the same so that there will be nothing to retard the rearward movement of the lever 18. The continued forward movement of the member 22 causes the member 23 to engage the lower end of the lever 18 and move the same forward

which through the link 17 snaps the barrel 11 rearwardly causing the cartridge carried thereby to engage the firing pin and explode the same.

The firing pin 33 is mounted in the block 34 carried by the upper end of the frame 1 and is longitudinally movable, and is provided intermediate its ends with the reduced portion 35 having the bevel portions 36 and 37. The block 34 is provided with a transverse vertical passage intersecting the passage carrying the firing pin and in which is arranged the vertically arranged safety lock 38. This lock 38 has a central opening to receive the reduced portion 35 of the firing pin 33 and is provided with the beveled walls 39 and 40 adapted to engage the beveled portions 36 and 37 of the reduced portion 35 of the firing pin. Thus it will be seen that by raising or lowering the safety lock 38 the firing pin is moved longitudinally for bringing it back within the block 34 so that as the barrel moves rearwardly the cartridge cap will not engage the firing pin for discharging the same. The lock 38 has stud 41 connected thereto and which extends out through a slot 42 in the side of the frame and the outer end of the stud is provided with a knob whereby the lock can be moved vertically. In order to positively lock the lock 38 in its lowered or raised position the stud 41 is provided with the normally outwardly spring pressed members 43 and 44 adapted to enter the notches 45 and 46 in the sides of the slots 42. In order to provide means for moving the members 43 and 44 inwardly out of the slots the knob 47 is slidably mounted upon the stud and normally outwardly spring held and upon a slight inward movement of the knob the members 43 and 44 are forced inwardly out of the slot.

The cartridge ejecting means comprises a spring member 48 mounted in the block 34 carrying the firing pin and projects out beyond the same and is adapted to be forced outwardly by the beading 49 carried by the rear end of the cartridge 50. In the rearward movement of the barrel the rim forces the spring member 48 outwardly until it has passed over the rim or bearing and catches over the same. The outward movement of the barrel leaves the cartridge held tightly against the block 34 until the barrel has passed the end of the empty cartridge, when the pressure of the member 48 snaps the shell out through the opening 51 in the side of the frame 1. Upon each reciprocation of the barrel this operation takes place and when the firing pin is receded the loaded cartridges are thrown out in the same manner, only the barrel in its outward travel has to move a slight distance farther before the cartridges are snapped out as allowance has to be made for the length of

the ball. The lower face of the barrel is provided with an elongated recess 52 into which extends the upper end of the lever 53, which is pivoted at 54 to the frame 1 and which extends rearwardly and is provided with a cartridge carrier 55 at its rear end and into which are forced the cartridges from the magazine 56. The pocket shaped member or cartridge carrier 55 is provided 10 with a spring 57 adapted to clasp the cartridge and hold it while the lever 53 is moving upwardly to bring the carrier opposite the barrel, so that the cartridge enters the barrel as it travels rearwardly and 15 forces the same against the firing pin to explode the cap. The cartridge carrier 55 is provided with a curved plate 56' which passes across the end of the magazine when the carrier is raised to prevent the cartridges from passing therefrom.

The cartridge carrier 55 has the side 66 extended upwardly above the opposite side and its rear edge curved as indicated 67. This curved face or edge engages the curved 25 portion 68 carried by the underside of the rear end of the barrel 11. The side 66 is of a length less than that of the cartridge so that the end thereof extends beyond the same. When the cartridge is raised the barrel 30 moves rearwardly, the end of the cartridge beyond the plate 66 enters the bore of the barrel. The continued rearward movement of the barrel causes the curved portion 68 of the barrel to engage the curved face 35 67 of the side 66 and gradually forces the same downwardly, the cartridge is held in the barrel and gradually forced in the barrel until it strikes the block 34. The carrier is gradually forced down in a position 40 opposite the rear end of the magazine, to receive another cartridge.

In order to prevent the cartridge from passing through the carrier I provide a pivoted spring stop 69, which is normally held 45 in its upward position by a spring 71. The upper end of the stop is provided with a lateral rearwardly extending portion 72 adapted to engage the lower edge of the firing pin block 34 in its upward movement and force 50 the same downwardly to prevent any possibility of the cartridge jamming.

The magazine 56 is of a rectangular form in cross section and of a length to receive the desired number of cartridges, the bore of the 55 magazine being round to receive and hold the cartridges in a straight position as shown in Fig. 4 of the drawings. The magazine has a follower 58 therein, which is provided with ears 59 traveling in grooves 60 and 61 60 to prevent the rotation of the same. The follower is normally held or pressed to the rear by a spring 60' for causing a tension on the cartridges to feed them therefrom. The rear end of the magazine is provided 65 with a catch 61, adapted to hold the car-

tridges in the magazine while it is being placed in the pistol but is released upon the magazine reaching its rearward limit of movement. This is accomplished by having a beveled faced wall 74 in the frame which 70 limits the inward movement of the magazine. The said stop is provided with a beveled face 75 engaging the beveled wall 74 for forcing the catch outwardly into the notch 77 and allow of the free passage of the 75 cartridge from the magazine. The sides of the magazine are provided with the notches 61' and 62' into which extend the sharp edges of the pivoted latches 63 and 64, pivoted in the frame 1. The latches are normally held in their inward position by means of the spring 65, all of which is clearly shown in Fig. 4 of the drawings.

The operation of the pistol is as follows: The magazine having been loaded with cartridges in the usual manner as heretofore described and placed in the frame until the catch releases them. One cartridge is forced therefrom into the carrier 66 and the pistol is ready for operation without any 85 preliminary operation, such as is necessary in the recoil automatic. The safety lock 38, if at safety, is moved downwardly, moving the firing pin outwardly beyond the block 34. The stock of the pistol is then gripped, 90 which forces the member 7 inwardly, which in turn forces the member 9 inwardly. The fork 26 of the member 22 engages the dog 28 and the same being carried by the lever 18, the said lever is forced forward and 95 through the medium of the link 17, the barrel is moved forward. The forward movement of the barrel raises the carrier 55 in a line with the rear end of the barrel. In the forward movement the member 22 carrying the fork 23 has engaged the bevel face 24, which gradually raises the member 26 so that its end passes over the dog and the 100 said dog drops into the slot 32. The continued forward movement of the member 22 causes the fork 23 to engage the lower end 105 of the lever 18 and move it rearwardly with a quick snap, carrying with it the barrel and picking up the cartridge from the carrier and bringing it against the firing pin 110 and exploding the cap. The grip of the stock is released and the regripping of the stock repeats the operation, which can be carried out very rapidly.

In order to provide additional means for locking the pistol so that it can not be fired I provide a pivoted lever 66 which has a laterally turned end extending through the plate 4 and has a cam portion 66 adapted to enter the slot 68 in the lower face of the barrel and when the same is moved into a position with cam shaped portion in slot the barrel can not be moved and thus the pistol is at safety.

Having thus fully described my inven- 130

- tion, what I claim and desire to secure by Letters Patent is:
1. An automatic pistol, comprising a frame carrying a stock and barrel, and means in the stock for causing one complete operation of the pistol by a single gripping of the stock.
  2. An automatic pistol, comprising a frame carrying a stock and a barrel, and a forwardly movable member in the stock adapted to cause one complete operation of the pistol during the forward movement of said member caused by the single gripping of the stock.
  3. An automatic pistol comprising a frame, means in the frame for ejecting the cartridge, placing another in the barrel and firing it, and a pivoted member in the stock and actuated by gripping the stock for operating said mechanism.
  4. An automatic pistol, comprising a frame, means in the frame for ejecting the cartridge, placing another in the barrel and firing it, and means actuated by gripping the stock for operating said mechanism by the single forward movement of a single member.
  5. An automatic pistol, comprising a frame, a stock carried thereby, a movable barrel for ejecting the cartridge and placing another therein and firing it by the rearward movement of the barrel, and means operated by the gripping of the stock for moving the barrel in both directions for causing one complete operation.
  6. An automatic pistol, comprising a frame, a stock carried thereby, a longitudinally movable barrel for ejecting the cartridge and placing another therein and firing it and a forwardly movable member operated by the gripping of the stock for operating the barrel in both directions.
  7. An automatic pistol, comprising a frame, a stock carried thereby, a longitudinally movable barrel ejecting the cartridge on its forward movement and placing another therein and firing it by the rearward movement of the barrel, a pivoted member in the stock and moved forward by the gripping thereof, and a forwardly moving member operated by the pivoted member in the stock for first moving the barrel forward, the continued movement of the member moving the barrel rearwardly.
  8. An automatic pistol, comprising a frame, a stock carried thereby, a longitudinally movable barrel ejecting the cartridge on its forward movement and simultaneously placing another in position to enter the barrel on its rearward movement, and the continued rearward movement of the barrel causing the cap to strike the firing pin and discharge the pistol, a pivoted member in the stock and operated by gripping the same, an intermediately pivoted lever in the frame, a link connecting the upper end of the lever to the barrel, and a forked member connected to the pivoted member in the stock and adapted to engage the lever above its pivot for forcing the barrel forward and the continued movement of the forked member engaging the lever below its pivot for moving it in its reverse direction and moving the barrel rearwardly.
  9. An automatic pistol, comprising a frame, a stock carried thereby, a longitudinally movable barrel in the frame and ejecting the cartridge on its forward movement, and simultaneously placing another in a position to enter the barrel on its rearward movement, and the continued rearward movement of the barrel firing the cartridge, a pivoted member in the stock and operated by gripping the same, an intermediately pivoted lever in the frame, a link connecting the upper end of the lever to the rear end of the barrel, and a forwardly sliding member pivotally connected to the pivoted member in the grip and adapted to engage the lever above its pivot on its first part of its movement for moving the barrel forward and to engage the lever below its pivot on its continued movement to reverse the direction of movement of the lever to move the barrel rearwardly.
  10. An automatic pistol, comprising a frame, a stock carried thereby, a longitudinally movable barrel in the frame, means for ejecting the cartridge on the forward movement of the barrel, a pivoted member operated by the forward movement of the barrel for raising a cartridge from the magazine and holding it in a line with the barrel to be picked up by the rearward movement thereof, a firing pin in line with the barrel, a safety means for receding the firing pin, a pivoted member in the stock and adapted to operate the barrel in a forward and rearward direction by a single movement thereof.
  11. An automatic pistol, comprising a frame, a stock carried thereby, a longitudinally movable barrel, ejecting means for the empty cartridge, means operated by the forward movement of the barrel for moving a cartridge in line with the barrel, a firing pin in line with the barrel, a safety means for receding the firing pin, a pivoted member carried by the stock, and means operated by the forward movement of the pivoted member for first moving the barrel forward and then moving it rearwardly.
  12. An automatic pistol, comprising a frame, a stock carried thereby, a longitudinally movable barrel, ejecting means, a magazine, means operated by the forward movement of the barrel for taking a cartridge from the magazine and holding it in line with the rear end of the barrel, a firing pin in line with the rear end of the barrel,

a safety means for receding the pin so that the cartridge can not strike it, a movable member in the stock and operated by gripping the same for moving the barrel forward on the first of its movement and the continued movement moving the barrel rearwardly with a snap to inclose the cartridge and cause it to strike the firing pin.

13. An automatic pistol, comprising a frame, a stock carried thereby, a longitudinally movable barrel, ejecting means, a magazine, means operated by the forward movement of the barrel for taking a cartridge from the magazine and holding it in line with the rear end of the barrel, a firing pin in line with the rear end of the barrel, means for locking the barrel against movement to prevent the accidental discharge of the pistol, and a movable member in the stock and operated by gripping the same for moving the barrel forward on the first part of its movement and the continued movement causing the rearward movement of the barrel with a quick snap to inclose the cartridge and cause it to strike the firing pin.

14. An automatic pistol, comprising a frame, a stock carried thereby, a longitudinally movable barrel ejecting the cartridge on its forward movement and simultaneously placing another in a position to enter the barrel on its rearward movement and the continued rearward movement of the barrel causing the cap to strike the firing pin, a pivoted member in the stock and operated by gripping the same, an intermediately pivoted lever in the frame, a link connecting the upper end of the lever to the barrel, a forked member pivotally connected to the pivoted member in the stock, a dog carried by the intermediately pivoted lever

above its pivot, and engaged by the upper prong of the forked member for forcing the barrel forward, the lower prong of the fork engaging an upwardly curved face of the frame to raise the same to cause the prong 45 to disengage the dog and the continued movement of the forked member causes the lower prong to engage the intermediately pivoted lever below its pivot for moving it in the reverse direction and moving the 50 barrel rearwardly with a rapid snap.

15. An automatic pistol, comprising a frame carrying a stock and a barrel, and a forwardly movable member in the stock adapted to cause a complete operation of the 55 pistol during the forward movement of said member caused by the gripping of the stock and means for causing the last part of the operation to be more rapid than the first for causing the firing of the cartridge. 60

16. An automatic pistol, comprising a frame carrying a stock and barrel, and a forwardly movable member in the stock adapted to cause a complete operation of the 65 pistol during the forward movement of said member caused by the gripping of the stock and means for causing the firing movement to be more rapid than the loading stroke.

17. An automatic pistol, comprising a frame, a stock carried thereby, a movable 70 barrel for ejecting the cartridge and placing another therein, and firing it by the movement of the barrel, and means operated by the continuous gripping of the stock for moving the barrel in both directions for 75 causing one complete operation, the firing movement of the barrel being more rapid than the loading.

In testimony whereof I affix my signature.
JOHN O. CROY.
